F. M. STRONG & T. ROSS.
PLATFORM SCALE.

No. 24,161.

Patented May 24, 1859.

UNITED STATES PATENT OFFICE.

FRANCIS M. STRONG AND THOMAS ROSS, OF BRANDON, VERMONT.

IMPROVEMENT IN WEIGHING-SCALES.

Specification forming part of Letters Patent No. 24,161, dated May 24, 1859.

To all whom it may concern:

Be it known that we, FRANCIS M. STRONG and THOMAS Ross, both of Brandon, in the county of Rutland and State of Vermont, have invented certain new and useful Improvements in Platform-Scales for Weighing; and we do hereby declare that the following is a full, clear, and exact description thereof, reference being had to the accompanying drawings, making part of this specification, in which—

Figure 1 is a plan showing the levers and the auxiliary intermediate frame on which the platform rests; Fig. 2, a front elevation showing the levers, intermediate frame, and platform, also giving a sectional view of the manner of constructing the intermediate frame and applying it and showing the manner of connecting the levers to the beam; Fig. 3, an enlarged section showing more clearly the construction of the intermediate frame and shafts; Fig. 4, an enlarged plan of portions of shaft A and arm B, showing the manner of attaching and securing them together; Fig. 5, an elevation of the same; Fig. 6, a horizontal section of the same; and Fig. 7, a view of the "poise" and a portion of the "beam," showing the manner of graduating them.

The shafts A A, Fig. 1, have knife-edges inserted at their centers (shown at P, Fig. 3) in "heads" formed to receive them at or near each extremity. These knife-edges are the fulcrum of the levers A B A B and rest upon a bearing secured to the frame or foundation. Inwardly from these knife-edges, parallel to and all equidistant therefrom, are other knife-edges, on which rests what we term the "intermediate frame" C, which supports the platform D. Concaves are formed at each corner of the intermediate frame to receive balls or spheres h, on which the platform rests, the under face of the said platform being in like manner formed with concave recesses to rest on the balls, as shown in Figs. 2 and 3. This manner of connection allows the platform to yield to any lateral movement without communicating it to the intermediate frame, thereby preventing the knife-edges from being abraded or injured.

The bearing-blocks d, Figs. 2 and 3, of the intermediate frame are not rigidly secured thereto, but are inserted in sockets, where they

have room to rock on "ribs" projecting from their upper sides, so that they may adjust themselves to the knife-edges on which they rest, and they have at the same time an endplay in the direction of the length of the frame C, so that they may adjust themselves to limited inequalities in the distance of the levers apart or variations of the length of the frame itself. These blocks are secured from dropping out of the sockets by staples e, Fig. 3. The intermediate frame C has also another peculiarity. It is made in two similar parts, each part forming one side and one end of the quadrangle, the two being joined at diagonally-opposite corners by links or other equivalent device, as shown in section in Fig. 2. This allows it to yield to the transverse movement of the knife-edges on which it rests, such transverse movement being caused by the oscillation of the levers in arcs of circles in the operation of weighing. The advantage of this will be more obvious in those scales called "drop-lever" scales, as in them the transverse movement is considerable, and not only has a tendency to abrade the knife-edges, but to otherwise impair the accuracy of the machine by cramping the free action of the levers. This frame C we sometimes construct of one piece; but this may be dispensed with when the levers themselves are hung in loops or links, as in such case it is not so essential that it should yield to the transverse movement of the knife-edges, as the levers themselves can then conform to the frame, although it is preferable to join it by links, as above described.

The arms B B have their extremities n n placed one above the other, and by thus placing them we attain a truly perpendicular connection of both with the beam, the upper one acting through the direct rod g, and the lower one acting upon the cross-bar at the lower end of the sling-rod g', which passes through an eye near the upper end of the rod g. This compound rod allows the levers to act freely, and the positions of the arms are such that the points of connection, as will be seen, are all in the same perpendicular line, and they both act in unison, whereas if they were separated sufficiently to lie in the same plane and have clearance the force would be transmitted to the beam from the two in oppositely-

inclined directions, and they would only to a certain extent counteract each other—a defect which becomes obvious when the body that is being weighed is moved from the center to either end of the platform. The beam F, Figs. 2 and 7, is graduated to the larger divisions, these being subdivided by the scale upon the sliding poise f, graduated on the principle of the "vernier."

The manner in which we "clutch" and secure the arms B B to the shafts A A is shown in Figs. 4, 5, and 6. The flange of the shaft A has a projection a, Figs. 4 and 5, against which a part of the arm B, projecting from the face of the flange forming the head, abuts. This last flange has a circular or annular tenon on its face, which enters a corresponding rabbit in the flange of the shaft A. The whole is secured by the single bolt b, shaft A being cast to receive the "nut" c.

The operation is as follows: The weight placed upon the platform acts through the balls or spheres and intermediate frame C upon the knife-edges of the shafts A A, tending to turn them, and consequently to depress the ends of the arms B B, and they actuate the beam where the weight is indicated by the poise and weights in the usual manner; and although we have above described but one mode of application of our said invention

we do not wish to be understood as limiting our claim of invention to such mode, as other modes may be adopted without changing the principle of our said invention.

What we claim as our invention, and desire to secure by Letters Patent, is—

1. The employment of an auxiliary frame substantially such as described, in combination with and interposed between the platform and levers, substantially as described, and for the purpose specified.

2. Constructing such intermediate frame in two parts connected by movable joints at the angles, substantially as and for the purpose specified.

3. The manner of constructing and inserting the bearing-blocks that rest on the knife-edges, substantially as and for the purpose specified.

4. Bringing the ends of the arms of the levers immediately one above the other, in combination with the mode of connecting the two with the beam by single and double connecting-rods, substantially as described, and for the purpose set forth.

FRANCIS M. STRONG.
THOMAS ROSS.
